UNITED STATES PATENT OFFICE.

FRANK A. SEBRING, OF SEBRING, OHIO.

DESIGN FOR A SUGAR-BOWL OR SIMILAR ARTICLE.

47,200.

Specification for Design.

Patented Apr. 6, 1915.

Application filed February 8, 1915. Serial No. 6,861. Term of patent 3½ years.

To all whom it may concern:

Be it known that I, FRANK A. SEBRING, a citizen of the United States, residing at Sebring, in the county of Mahoning and State of Ohio, have invented a new, original, and ornamental Design for a Sugar-Bowl or Similar Article, of which the following is a specification, reference being had to the accompanying drawing, forming part thereof.

In the drawings: Figure 1 is a side elevation of a sugar bowl or similar article, embodying my new design. Fig. 2 is a top plan view of the sugar bowl.

I claim:

The ornamental design for a sugar bowl or similar article, substantially as shown.

FRANK A. SEBRING.
